United States Patent Office

Des. 185,176
Patented May 12, 1959

185,176

TEXTILE FABRIC OR SIMILAR ARTICLE

Sylvia Sherman, New York, N.Y., assignor to Fenwick
Textiles, Inc., New York, N.Y.

Application December 30, 1957, Serial No. 49,065

Term of patent 3½ years

(Cl. D92—1)

FIG. 1

FIG. 2

Fig. 1 is a plan view of a textile fabric or similar article showing my new design. The design unit is contained between the dot and dash lines, which unit is repeated in successive relation as indicated by the extensions beyond the unit boundaries.

Fig. 2 is an enlarged fragmentary view of Fig. 1.

I claim:

The ornamental design for a textile fabric or similar article, substantially as shown and described.
